US00D635206S

(12) **United States Design Patent**
Henniger

(10) **Patent No.:** **US D635,206 S**
(45) **Date of Patent:** **** Mar. 29, 2011**

(54) **EXERCISE RACK**

(75) Inventor: **William Henniger**, Columbus, OH (US)

(73) Assignee: **Coulter Ventures, LLC**, Logan, OH
(US)

(**) Term: **14 Years**

(21) Appl. No.: **29/379,928**

(22) Filed: **Nov. 26, 2010**

Related U.S. Application Data

(63) Continuation of application No. 29/368,730, filed on Aug. 27, 2010.

(51) **LOC (9) Cl.** **21-02**

(52) **U.S. Cl.** **D21/691**

(58) **Field of Classification Search** **D21/662, D21/686, 691, 694, 826; 482/36, 39, 94, 482/98-99, 101, 104, 143, 163.1, 188, 188.1; D6/329, 449, 480-490, 495; D25/6, 126**

See application file for complete search history.

(57) **CLAIM**

The ornamental design for an exercise rack, as shown and described.

DESCRIPTION

FIG. 1 is a perspective view of a first embodiment of an exercise rack showing my new design;

FIG. 2 is a front elevation view thereof;

FIG. 3 is a top plan view thereof;

FIG. 4 is a bottom plan view thereof;

FIG. 5 is a left elevation view thereof;

FIG. 6 is a right elevation view thereof;

FIG. 7 is a perspective view of a second embodiment of an exercise rack showing my new design;

FIG. 8 is a front elevation view thereof;

FIG. 9 is a top plan view thereof;

FIG. 10 is a bottom plan view thereof;

FIG. 11 is a left elevation view thereof; and,

FIG. 12 is a right elevation view thereof.

The broken line showing is for the purpose of illustrating environmental structure and forms no part of the claimed design.

1 Claim, 8 Drawing Sheets
